UNITED STATES PATENT OFFICE.

VINCENT PASCUCCI, OF CORONA, NEW YORK.

DESIGN FOR A HORN.

40,698.

Specification for Design.

Patented May 17, 1910.

Application filed March 16, 1910. Serial No. 549,805. Term of patent 7 years.

To all whom it may concern:

Be it known that I, VINCENT PASCUCCI, a citizen of the United States, and a resident of Corona, in the county of Queens and State of New York, have invented a new, original, and ornamental Design for a Horn, of which the following is a specification, reference being had to the accompanying drawing, forming part thereof.

The figure is a side elevation view of a horn, showing my new design.

I claim—

The ornamental design for a horn, as shown.

VINCENT PASCUCCI.
